UNITED STATES PATENT OFFICE.

PHILIP A. MYERS, OF ASHLAND, OHIO, ASSIGNOR TO F. E. MYERS & BRO., OF SAME PLACE.

DESIGN FOR A PUMP-BODY.

SPECIFICATION forming part of Design No. 33,111, dated August 21, 1900.

Application filed June 6, 1900. Serial No. 19,329. Term of patent 14 years.

To all whom it may concern:

Be it known that I, PHILIP A. MYERS, a citizen of the United States, residing at Ashland, in the county of Ashland and State of Ohio, 5 have invented and produced a new and original Design for a Pump-Body Casing, of which the following is a specification.

In the accompanying drawings, giving different views of my design, Figure 1 is a front 10 view of the pump-body. Fig. 2 is a side elevation. Fig. 3 is a rear elevation, and Fig. 4 is a plan view.

The leading feature of the invention resides in the shape of the base and the body 15 of the pump supported thereby, and a further distinctive feature of the design is the position and shape of the spout. The base of the pump A is hollow, and its side walls have elongated openings, the base tapering 20 slightly on all four sides to the lower flange a.

Above the base A the body of the pump is

substantially cylindrical and overhangs the base at each end. This is shown at B. The cylindrical body has surmounting it a casting substantially rectangular, but with a 25 somewhat varied outline as well as surface configuration, this being shown in the plan view, Fig. 4, as well as in the elevations. This is shown at C. A curved spout portion D extends from the center of the part C. A 30 tubular projection E extends from one side of the cylinder, as shown in Figs. 1 and 3. The ends of the cylinder are shown, respectively, in Figs. 1 and 3.

What I claim is--

The design for a pump body and casing as herein shown and described.

PHILIP A. MYERS.
